UNITED STATES PATENT OFFICE.

GLEN R. DUGGAN, OF BINGER, OKLAHOMA.

FUNNEL.

Application filed August 24, 1923. Serial No. 659,114.

To all whom it may concern:

Be it known that I, GLEN R. DUGGAN, a citizen of the United States, residing at Binger, in the county of Caddo and State 5 of Oklahoma, have invented certain new and useful Improvements in Funnels, of which the following is a specification.

This invention relates to measuring and filling devices and has for its principal object to provide a funnel for the purpose 10 of measuring and filling bottles or the like in an efficient manner.

Another object of this invention is to provide a funnel which will take up the 15 overflow of liquid and the vacuum created by the outlet portion of the funnel and the mouth of the bottle or receptacle which is being filled in conjunction with means attached to the outlet end of the funnel will 20 force the overflowing liquid into the funnel and thereby eliminate any necessity of waste.

A further object of the invention is to provide a funnel with a pipe line which 25 extends along the inner side wall of the funnel from the receiving end to the mouth of the outlet portion for receiving a metallic rod which carries a cork at the extreme lower end thereof for the purpose of 30 closing the outlet end of the funnel when desired.

A still further object is to provide a funnel with means for measuring and filling receptacles and one by which the user may 35 have ready access to the various parts thereof for the purpose of removing waste which may be accumulated in the pipe line.

Other objects of the invention will appear 40 upon consideration of the following detailed description and accompanying drawings wherein:

Figure 1 is a side elevation of the invention as applied to the mouth of a bottle.

Figure 2 is a top plan view of the invention, and

Figure 3 is a side elevation showing the device partly in section.

Referring now to the drawing wherein like characters of reference denote corresponding parts, the numeral 5 indicates a funnel having peripheral beads 6 formed thereon and a pipe line 7 extending downwardly within the said funnel along the side wall thereof, and said pipe line extends from the top or the mouth of the 55 funnel to the mouth of the outlet portion.

The pipe line is designed to receive a metallic rod 8 which projects beyond the top and bottom of the funnel and the extreme lower end of said rod is provided with a 60 cork 9 and is securely held in position by the upturned portion of the rod as indicated at 10. The usual handle 11 is provided on one side of the funnel and has a bearing member 12 secured thereto at the 65 underside thereof and a spring 13 which has its rear end pivotally connected to the handle portion as at 14 and extended forwardly to permit the slotted portion 15 to engage the upper end of the rod 8. A ring 70 member 16 is carried by the handle and is sufficiently supported to engage the spring member to force the same into operative or inoperative position. The operator of this device by exerting a pressure upon the 75 spring may move the ring toward the forward or rearward end of the spring for forcing the cork into or out of the outlet end of the funnel. The spring member is positioned between nuts 17, and by removing 80 said nuts access may be had to the pipe line for removing waste which may accumulate therein.

When it is desired to use the funnel for the purpose for which it has been invented, 85 it is simply necessary that the operator place the hand upon the spring member and move the ring member toward the forward end of the spring so as to force the cork out of the outlet end of the funnel spout 90 and thereby allow the liquid to flow from the funnel into the receptacle which is being filled, and when it is desired to force the cork into the outlet end of the spout, the ring member may be moved toward the 95 rear end of the spring so as to engage the same and the action of the spring will force the cork into the outlet end of the spout thereby taking up the overflow of liquid 100 to prevent waste.

What I claim is:

In combination with a funnel having a valve normally urged to closing position by a leaf spring attached to the funnel handle and to the valve rod, a spring manipulating and locking ring pivoted to the handle intermediate the valve rod and point of attachment of the spring to the funnel handle.

In testimony whereof, I have affixed my signature.

GLEN R. DUGGAN.
